WALTER M. CROSS, DECEASED, ASSIGNOR TO CROSS COAL-O-MATIC COMPANY, OF
KANSAS CITY, MISSOURI, A CORPORATION OF MISSOURI

UNDERFEED STOKER

Application filed November 8, 1928. Serial No. 318,022.

This invention relates to improvements in an automatic underfeed stoker, and refers more particularly to a draft control by means of which a portion of the air draft supplied to the main combustion retort is diverted and distributed around the space surrounding the retort to assist in completely consuming the fuel after it has passed the lip or circumference of the retort. This auxiliary draft is preferably taken from the main air draft duct through a controlled damper arrangement so that the pressure on the space or grates surrounding the main retort will be a differential and lower pressure than the pressure of the air supplied to the combustion retort through the main air draft duct.

Fig. 1 is a side view, partly in elevation and partly in section, of the stoker installation.

Fig. 2 is a view taken along the line 2—2 in Fig. 1.

Fig. 3 is a view taken along the line 3—3 in Fig. 1.

Fig. 4 is a view taken along the line 4—4 in Fig. 3.

Fig. 5 is an enlarged detail of the removable and adjustable grates surrounding the combustion retort.

Referring to the drawings, at 1 is shown diagrammatically the masonry portion of a furnace installation upon which is mounted a boiler 2 having flues 3 and a combustion space 4.

Mounted in the furnace and below the combustion space of the boiler is positioned the combustion retort 5. The combustion retort consists of a fuel pot 6 surrounded by an air duct or jacket 7. In the throat of the fuel pot are slotted tiles 8. The slots or tuyères 9 communicate with the air duct 7 so that air supplied from the blower or fan 10 through the duct 11 and jacketed pipe 12 to the air duct 7 surrounding the fire pot is introduced into the bed of coal through the tuyères 9 in the throat of the fire pot. The fuel is supplied from a hopper 13 by means of a screw conveyor 14 rotated by means of the motor 15 which drives both the fan and the screw conveyor by suitable gears and driving connections enclosed within the cas-

ing 16 and forming no part of the present invention. This fuel, which is preferably coal, is fed from the hopper by means of the screw 14 through the fuel pipe 17 communicating between the hopper and the combustion pot 55 or retort.

Surrounding the retort are positioned a set of grates 18 which are removable and adjustable. The lower, flat horizontal portion, designated 18^a, of the grate, is supported upon a shoulder or wall such as that shown at 19 in Fig. 3, and upon the edge of the combustion retort. A vertical portion 18^b and the upper horizontal portion 18^c form a hollowed out space beneath each one of the 65 grates. A second vertical portion 18^d is slotted at 20 so that the auxiliary air introduced below the grates flows through the hollow portion of the grates and out into the bed of coal or fuel through the ducts 20 in the 70 direction shown by the arrows in Fig. 5.

The supporting grates 18 are adjustable, that is, they may be pushed together or extended as long as there is an opening or hollow portion formed beneath the grates to permit the passage of air through the slots 20. Also they may be easily removed or replaced as they are set without fastening on supports to cover the ash pit space surrounding the 75 combustion retort.

To supply this auxiliary air to the tuyère grates 18 surrounding the combustion retort, a closure or damper 21 is hinged to the air jacket 7 of the retort. This closure or damper covers an opening or port and is adjustable 85 by means of a manually controlled damper rod 22. This closure serves to control the auxiliary air supplied beneath the tuyère grates 18 and regulates the differential air draft or air pressure of the induced air supplied as draft to both the combustion retort and the tuyère grates surrounding the combustion retort.

In the burning of bituminous coal, it is possible by this construction to vary the pressure in the tuyères 9 and supply at the same time a differential lower pressure to the tuyère grates 18 surrounding the combustion retort of the stoker, thus making it possible to effect a more complete and efficient burning 95 100

of the coal in the combustion retort and the tuyère grates respectively. According to the volatile constituents present in the coal to be burned, it will be necessary to regulate the amount of air supplied to the retort and to the tuyère grates. Also to achieve smokeless combustion the differential pressures beneath the retort and the tuyère grates may be governed by means of the damper or shutter 21 which permits a portion of the draft to escape into the ash pit and rise through the tuyère grates to pass through the partially consumed fuel bed supported on the tuyère grates. It is desired to so control the differential pressures in the retort and beneath the tuyère grates that the volatile hydrocarbons are exhausted or burned from the fuel before it is crowded out of the retort onto the tuyère grates surrounding the retort. Thus the volatile hydrocarbons will be burned by the air discharged from the retort tuyères 9 and the carbonaceous material primarily taken care of or burned while passing over the tuyère grates 18.

25 The ash pit of the boiler is sealed so that the pressure beneath the tuyère grates cannot escape except through the openings 20 in the grates themselves. No ashes are allowed to fall through the grates and the tuyères or air passages extend horizontally through a vertical portion of the grates, thus preventing the clogging of the air draft passageways by the accumulation of dirt and ashes.

35 I claim as my invention:

An underfeed stoker having in combination a combustion retort, a fuel supply duct, a fuel feeding means mounted in said duct, an air supply duct positioned around said fuel supply duct and said combustion retort whereby the air supply is heated to increase the thermodynamic efficiency, air supply openings in said combustion retort, grates provided with air openings surrounding the combustion retort, an air chamber positioned around the air supply duct, said chamber being in communication with the combustion space by means of said grate opening and a bleeder damper adapted to admit air into said air chamber from the air duct, thereby permitting a reduction of the air supply to the combustion retort and admitting air to the grate openings enabling a flexible combustion control without varying the air duct pressure, and allowing a complete combustion of the fuel which overflows the combustion retort to the grates.

WALTER M. CROSS.
